UNITED STATES PATENT OFFICE.

WALTER E. BEEDE, OF NEW YORK, N. Y., ASSIGNOR TO AMERICAN EVER READY COMPANY, A CORPORATION OF NEW YORK.

PORTABLE ELECTRICAL MEASURING INSTRUMENT.

966,421.

Specification of Letters Patent. Patented Aug. 9, 1910.

Application filed December 21, 1909. Serial No. 534,256.

To all whom it may concern:

Be it known that I, WALTER E. BEEDE, a citizen of the United States, residing at the borough of Manhattan, city of New York, 5 in the county of New York and State of New York, have invented certain new and useful Improvements in Portable Electrical Measuring Instruments, of which the following is a specification, reference being had 10 therein to the accompanying drawings, forming part thereof.

My invention relates to portable electrical measuring instruments, such as are adapted to be carried in the pocket and which in general appearance resemble a watch.

The principal objects of my invention are compactness, simplicity and economy of construction, durability, reliability, and accuracy and sensitiveness of operation. My 20 invention includes certain combinations of parts adapted to accomplish these objects.

In carrying out my invention, I provide a straight flattened solenoid coil and a flat, tapered and curved armature core adapted 25 to pass through the solenoid coil, an arbor being provided for the armature core, and such arbor carrying also a pointer and a counterbalance.

My invention also includes three members, 30 to wit, a pointer, an armature and a counterbalance concentrically mounted each such member being rotatively unbalanced and each being relatively rotatively adjustable to secure a common rotative balance.

My invention also includes, in combination, a base plate provided with an annulus forming a shallow cup, the base plate also being provided with struck-up portions, respectively forming a terminal for the solenoid coil, a bearing for the arbor and an anchor for a solenoid-opposing spring connected to the arbor.

I shall now describe my invention with reference to the drawings and shall there- 45 after point out my invention in claims.

Figure 1 is a rear view of the instrument with the rear cover removed and the casing partly broken away. Fig. 2 is an end view looking from the right of Fig. 1 and 50 with the casing partly broken away. Fig. 3

is a front view of the instrument. Fig. 4 is a detail view of the rotatable arbor and its adjuncts as seen in Fig. 2.

In the illustrated embodiment of the invention, the working parts of the device are shown as inclosed in a circular flattened casing of the watch case type, comprising a base plate 1 provided with an annulus 2 forming with the base plate 1 a shallow cup. The casing includes a rear cover 3 and a front cover 4, the latter being provided with a transparent crystal 5. A straight, flattened solenoid coil 6 is located substantially centrally of the casing with one of its flattened sides adjacent to the rear cover 3 and the other of its flattened sides adjacent to the base plate 1, to which the solenoid coil is secured by a sheet metal strap 7 passing through the coil and attached at its ends to the base plate 1 by screw-headed bolts 8 and nuts 9. A standard 10, forming a terminal connection for one of the terminals of the solenoid coil, is struck up from the base plate 1, leaving an opening 11 in the base plate, the terminal of the coil 6 being soldered to the standard 10. The other terminal of the coil 6 is soldered to a curved metal strip 12 connected to a contact terminal 13 passing to the outside of the casing through an insulating ring 14 seated in an opening in the annulus 2. Any part of the casing may be employed as the other contact terminal in using the device, but usually a separate and attached contact terminal is employed having a short flexible 85 wire terminating in a plug adapted to be inserted in a socket 15 in the stem 16. The solenoid coil 6 coacts with a pivoted sheet metal armature core 17 mounted on a rotatable arbor 18. The arbor 18 is located 90 in an eccentric relation to the casing and at one side of the solenoid coil substantially equidistant from the ends of such coil, as clearly shown in Fig. 1. The armature core 17 has, as shown in Fig. 1, a portion extending outward from the arbor and merging into a tapered curved portion concentric with the arbor 18 and entering the solenoid coil 6. Besides the armature core 17, the arbor 18 also has mounted thereon a coun- 100

terbalance 19, a spring drum 20, a pointer 21, and two end disks 22. In the illustrated embodiment of the invention the end disks or retaining disks 22, the pointer 21 and the spring drum 20 are fixed on or mounted to rotate with the arbor 18, while the armature core 17 and the counterbalance 19 are frictionally held by a strong frictional resistance between the spring drum 20 and one of the end disks 22. This construction permits of an accurate adjustment and correct balancing of the movable parts of the device.

The arbor 18 is provided with cone-shaped ends and has a bearing at one end in the base plate 1 and at the other end in a bearing arm 23, cut and struck up from the base plate 1, leaving therein an opening 24, and extending first outward from and then substantially parallel to the base plate, as shown in Figs. 1 and 2. A volute ribbon spring 25 is secured at its inner end to the spring drum 20 and at its outer end is soldered to an anchor post 26 struck up from the base plate 1, leaving an opening 27. The spring 25 is adapted to rotate the arbor 18 and the parts carried thereby, including the armature core 17, in opposition to the solenoid coil 6, and causes the armature core 17, when not attracted by the solenoid coil, to abut against the annulus 2 of the casing which is in its path, as shown in Fig. 1.

The instrument has a dial 28 secured to the front side of the base plate 1 by the bolts 8; and the dial is provided with a suitably calibrated direct reading scale 29, over which the pointer 21 is adapted to move. The pointer 21 is bent, as best shown in Fig. 4, so as to pass through the hole 24 in the base plate and through a smaller arcuate slot 30 in the dial 28.

When the coils of the solenoid coil 6 are energized by the passing of a current, the tapered armature core 17 will be drawn through the solenoid coil from the narrow and toward the wider portion of the armature core in opposition to the opposing rotational effect of the spring 25, and the pointer 21 will be moved to the indication on the scale 29 corresponding to the magnitude of the electrical energy being measured.

In its illustrated embodiment, the instrument is shown as adapted for use as an ammeter, but the principles of the invention could as well be embodied in a slightly modified instrument adapted to be used as a voltmeter, or in an instrument adapted for use as both an ammeter and a voltmeter, that is to say, a volt-ammeter.

It is obvious that various modifications may be made in the construction shown and above particularly described within the principle and scope of my invention.

I claim:

1. In an electrical measuring instrument, 65 the combination of an arbor, three members mounted thereon, to wit, a pointer, an armature and a counter-balance weight, each such member being rotatively unbalanced in reference to the axis of the arbor and each such member being rotatively adjustable in reference to each of the other members about the axis of the arbor, a conductive coil controlling the armature, and means opposing the attractive action of the conductive coil 75 on the armature.

2. A portable electrical measuring instrument comprising a casing of the watch-case type, a straight flattened solenoid coil arranged with its flattened sides turned toward the flattened sides of the casing, an arbor located in an eccentric relation to the casing and at one side of the solenoid coil and substantially equidistant from the ends of such coil, a sheet metal armature core 85 mounted on the arbor and having a portion extending outward from the arbor and a tapered curved portion concentric with the arbor and actuated by the solenoid, a pointer carried by the arbor, a scale for the pointer, 90 a spring surrounding the arbor and arranged to oppose the solenoid coil, and a rotatively adjustable counterbalance mounted on the arbor.

3. A portable electrical measuring instrument comprising a flattened casing of circular contour, a straight flattened solenoid coil arranged with its flattened sides adjacent to the flattened sides of the casing, a pivoted sheet metal armature core having a portion extending outward from the pivot and a tapered curved portion concentric with the pivot and adapted to pass through the solenoid coil, an arbor forming a pivot for the armature core located in an eccentric relation to the casing and at one side of the solenoid coil and substantially equidistant from its ends, a pointer carried by the arbor, a scale for the pointer, a counterbalance for the pointer and armature core carried by the arbor, and a spring tending to draw the armature core through the solenoid coil from the wider toward the narrower portion of the armature core.

4. A portable electrical measuring instrument comprising a flattened casing of circular contour including front and rear covers and a base plate provided with an annulus forming a shallow cup, a solenoid coil supported by the base plate, a terminal connection for the coil struck up from the base plate, a pivoted armature core coactive with the coil, an arbor forming a pivot for the armature core, a pointer carried by the arbor, a counterbalance for the pointer and armature carried by the arbor, the base plate

having a bearing therein for one end of the arbor, a bearing for the other end of the arbor struck up from the base plate, a volute spring surrounding the arbor and connected 5 at one end thereto, and an anchor for the other end of the spring struck up from the base plate, the spring being adapted to oppose the attractive action of the solenoid coil and the annulus of the casing forming

an abutment for the armature core in its 10 non-indicating position.

In testimony whereof I have affixed my signature in presence of two witnesses.

WALTER E. BEEDE.
